TOY TOP

Filed Aug. 30, 1930

FIG. 1.

FIG. 2.

FIG. 4.

Inventor
John Zaurrini

By *Watson E. Coleman*
Attorney

UNITED STATES PATENT OFFICE

JOHN ZAURRINI, OF DETROIT, MICHIGAN

TOY TOP

Application filed August 30, 1930. Serial No. 479,059.

The present invention relates to toys and more particularly to toy tops or the like.

An object of this invention is to provide a top having a rotatable element which is so constructed as to permit the ready spinning thereof by a child or the like.

Another object of this invention is to provide in a top of this character a means by which the top may be readily spun or rotated, the spinning means comprising an elongated tubular handle structure, which is adapted to support the top in the initial rotation or spinning thereof.

A further object of this invention is to provide a combined handle and top which may be readily and cheaply manufactured.

The above and various other objects and advantages of this invention will in part be described in and in part be understood from the following detailed description of the present preferred embodiment, the same being illustrated in the accompanying drawings wherein,

Fig. 1 is a detail side elevation of a top constructed according to the preferred embodiment of this invention, which is mounted in a handle, the handle being shown in longitudinal section.

Fig. 2 is a detail top plan view of the device.

Fig. 3 is an enlarged sectional view taken on the line 3-3 of Fig. 1.

Fig. 4 is a sectional view partly in detail taken substantially on the line 4-4 of Fig. 1.

Referring to the drawings wherein like numerals of reference indicate corresponding parts throughout the several views, the numeral 10 designates generally a top constructed according to the preferred embodiment of this invention, and the numeral 11 designates generally a handle which is constructed according to the preferred embodiment of this invention, and adapted to removably receive the top 10.

The top 10 comprises a body portion 12 and a depending spindle 13, the spindle 13 being secured to the top portion 12 in any desired manner. A substantially spherical member 14 is secured to the spindle 13 intermediate the ends thereof, and the spherical

member 14 is provided with an annular groove or recess 15 for removably receiving a flexible element 16, the flexible element preferably comprising a cord or the like, which is adapted to be wound about the member 14 and positioned in the groove 15.

The handle 11 comprises a relatively elongated tubular member which is provided at one end thereof with a pair of diametrically positioned slots 17, which open through the outer end of the handle 11, the outer ends of the slots terminating in flaring or rounded portions 18 so as to facilitate the placement of the spindle 13 therein. The handle 11 may be provided with suitable depressions 19 intermediate the ends thereof so as to facilitate the grasping of the handle in the hand.

In the operation of this device the cord 16 may be wound on the spool 14, the free end of the cord being projected rearwardly through the handle 11, so as to permit the free end to be grasped by the hand.

The spindle 13 is adapted to be placed in the forward end of the handle 11, being mounted in the slotted portion 17 and engaging against the rear end of the slot 17.

The cord 16 may be pulled rearwardly and the rearward movement of the cord 16 will rotate the top 10 within the handle 11. When the cord 16 has been completely unwound or withdrawn from the spool member 14, the handle may be pulled rearwardly of the top 10 so as to permit the top 10 to have free rotation on any desired flat surface.

It will be obvious from the foregoing that a relatively simple toy has been constructed, which may be readily operated by a child and that the toy may be constructed of any desired material.

It is, of course, understood that various changes and modifications may be made in the details of construction and design of the above specifically described embodiment of this invention without departing from the spirit thereof, such changes and modifications being restricted only by the scope of the following claim:

What is claimed is:—

A toy of the character described comprising in combination, an elongated hollow

handle having a cylindrical bore extending longitudinally of said handle, a pair of diametrically opposed open ended slots communicating with said bore at the forward end thereof, a rotatable top, said rotatable top comprising a body portion, a spindle, and a substantially spherical-shaped spool secured to said spindle intermediate the ends thereof and rotatably engageable within said bore, said spool having a peripheral groove there-in and having a diameter greater than the width of said slots, and a flexible member removably wound about said spool and positioned in the grooved portion thereof, said flexible member having one end thereof free and projected rearwardly through the tubular handle whereby to permit pulling of the flexible member through the handle, said flexible member upon rearward movement thereof through the handle being adapted to rotate said top on said handle, rearward movement of the handle upon unwinding of the flexible element releasing said top member for rotation independently of said handle.

25 In testimony whereof I hereunto affix my signature.

JOHN ZAURRINI.
